[57] CLAIM

The ornamental design for a casing for stampers, as shown and described.

DESCRIPTION

FIG. 1 is a perspective view of the casing for stampers according to my design;

FIG. 2 is a front elevational view of the casing for stampers;

FIG. 3 is a top plan view thereof;

FIG. 4 is a bottom plan view thereof;

FIG. 5 is a right side elevational view thereof, the left side elevational view being a mirror image thereof;

FIG. 6 is a view in section taken along line 6—6 of FIG. 3;

FIG. 7 is a view in section taken along line 7—7 of FIG. 3;

FIG. 8 is a view in section taken along line 8—8 of FIG. 3, and,

FIG. 9 is a perspective view showing how to stack the casings with stampers contained in the casings.

The broken line showing of the stampers and the other casing in FIG. 9 is for illustrative purposes only and forms no part of the claimed design.
